UNITED STATES PATENT OFFICE.

ANNA COLEMAN AND JOHN A. COLEMAN, OF LOS ANGELES, CALIFORNIA.

SUN AND AIR BATH CABINET.

Application filed June 25, 1925. Serial No. 39,548.

Our invention relates to a new and improved cabinet which preferably comprises a metal frame and a canvas cover that is of a dimension, 6 x 8 x 6 feet for taking nude sun and air baths, (heliotherapy and areotherapy) and which can be larger or smaller if so desired.

An object of the invention is to provide a sun-air bath cabinet that is so constructed and arranged as to permit the canvas to be slipped on the frame as it is assembled; and also to provide a means in each of the upper corners of the frame for the extension of the frame and making the surrounding canvas taut.

Further objects of our invention are:—

1. To provide a simple, convenient and inexpensive portable cabinet that is constructed and arranged so that one person may put it together in twenty or twenty-five minutes, and take it apart in ten minutes.

2. To provide a sun and air bath cabinet having a cross gable rod on which divided dark colored curtains can be suspended so as to shade or screen any part of a person using the cabinet from the sun's rays, or expose any part of the body to the sun's rays, thus eliminating the use of sun glasses, sun shades and other primitive methods of protecting the eyes, head, or other portions of the body while taking nude sun baths.

3. To provide a sun and air bath cabinet so constructed and arranged that the technique of heliotherapy may be applied and carried out with the greatest degree of safety and accuracy.

4. To provide a light demountable sun and air bath cabinet, that is simple in construction and easy in operation, so that any person even one greatly weakened by illness may use or operate the same for sun and air treatments of the body and the general application of heliotherapy and areotherapy.

5. To provide a sun and air bath cabinet having lower and upper frame portions that are adapted to be detachably connected by means of corner elbows that are provided with integral extensions that are adapted to cooperate with sleeves to hold the frame portions together.

The accompanying drawing illustrates the invention.

Fig. 1 is a perspective view of the "sun-air" bath cabinet when completely set up and ready for use.

Fig. 2 is a perspective view of the metal frame of said "sun-air" bath cabinet.

Fig. 3 is a cross-sectional view of the elbow connections on the upper cross rod of the frame showing the end connection of the curtain cross rod; and the numbers, 43, 44, 45, 46, 47 and 50, correspond to the like numbers in Fig. 2, indicating the particular part of the frame which is shown in the cross-sectional view under Fig. 3.

Fig. 4 is a cross-sectional view of one of the four upper corners of the frame showing the mechanism of the extension device in a contracted or normal position.

Fig. 5 is a cross-sectional view of one of the upper corners of the frame showing the mechanism of the extension device in an extended position whereby the upper and lower portions of the frame are separated to stretch taut the canvas surrounding the frame.

The component parts of the frame as shown in Fig. 2 are described as follows:

1, 2, 3, and 4 indicate $\frac{1}{2}$ " metal caps which are used as the feet of the cabinet.

5, 6, 7, and 8 indicate $\frac{1}{2}$ " x 3" nipples.

9, 10, 11, and 12 are $\frac{1}{2}$ " T's.

13 and 15 are $\frac{1}{2}$ " base pipes 7', 9 $\frac{5}{8}$ " long and threaded at both ends.

14 represents a $\frac{1}{2}$ " base pipe, 5', 9 $\frac{5}{8}$ " long.

16 represents a piece of base pipe $\frac{1}{2}$ " by 5', 7 $\frac{1}{4}$ ", on one end of which is attached the female half of a $\frac{1}{2}$ " coupling, indicated as 17.

18 is a $\frac{1}{2}$ " x $\frac{3}{4}$ " nipple. The male half of 17 is screwed on 18.

19, 20, 21, and 22 are upright corner posts that preferably are pipes 5', 6" long, threaded at both ends, the upper ends being threaded two inches so as to permit the upward movement of 23, 24, 25, and 26 for extension of frame.

23, 24, 25, and 26 are $\frac{1}{2}$ " x 2" sleeves or couplings which are screwed on the upper end of pipes 19, 20, 21, and 22 respectively.

27, 29, 33, and 35 are $\frac{3}{8}$ " elbows with a $\frac{3}{8}$ " x $\frac{1}{2}$ " round projection which is indicated by 51 in Figs. 4 and 5. This projection 51 is designed to be fitted into the openings, in the upper ends of pipes 19, 20, 21, and 22 and also in the open ends of the sleeves 23, 24, 25, and 26 as shown in Figs. 4 and 5.

28 and 34 are pieces of pipe $\frac{3}{8}$ " x 5', 9 $\frac{5}{8}$ "

long that connects the respective elbow pipes 27, 29 and 33, 35.

30, 32, are top pipes $\frac{3}{8}$ " x $3\frac{1}{2}$ " long, connected by a center T pipe 31 and these 5 pipes have their other ends connected to the elbow pipes 29 and 33. 36 is a pipe $\frac{3}{8}$ " x $3\frac{1}{2}$ ".

38 is a top pipe $\frac{3}{8}$ " x 33" long.

39 is a $\frac{3}{8}$ " coupling.

10 40 is a $\frac{3}{8}$ " x $\frac{3}{4}$ " nipple, attached to the elbow pipe 27. The parts 36, 37, 38 and 39 form a detachable connection between the elbow pipe 35 and nipple 40.

31 and 37 are $\frac{1}{4}$ " x $\frac{3}{8}$ " T's.

15 41 and 49 are $\frac{1}{4}$ " x $\frac{3}{4}$ " nipples.

42 and 48 are $\frac{1}{4}$ " couplings.

43 and 47 are pieces of pipe $\frac{1}{4}$ " x 14" long.

44 and 46 are $\frac{1}{4}$ " elbows.

20 45 is a piece of pipe $\frac{1}{4}$ " x 7', $9\frac{5}{8}$ " long.

50 is a metal rod $\frac{1}{4}$ " x 7', 9" long on which the curtain rings are adapted to slide.

The size of the cabinet can be increased or diminished without changing any of its 25 combinations or arrangements. We have selected the size 6' x 8' because it is a better size for all around purposes.

The size of pipe may be increased according to the climatic conditions; that is, where 30 winds are more prevalent the pipe or tubing may be increased to $\frac{1}{2}$ " or $\frac{3}{4}$ " all around, or even more if necessary.

The canvas used on the 6' x 8' frame is preferably made in one piece 6' 2" wide and 35 28' 3" long. The top of the canvas is turned over and sewed to form an upper casing. The canvas casing is provided with slits adjacent the points where the corners of the frame will be when the cabinet is assembled 40 so as to permit the top pipes to be extended therethrough and connections of the frame parts made. A strip of canvas about three inches wide and preferably the full length of the extended cabinet cover is sewed on the 45 canvas about four inches above its bottom edge to form another casing through which the base pipes can be extended, and this casing is also provided with slits similar to the slits in the upper casing and for similar purposes.

In assembling the cabinet the operation consists of first securing the parts 1, 5 and 9 together and then extending pipe 13 through its respective portion of the lower casing 55 of the canvas and securing it to the T pipe 9. Then the parts 2, 6 and 10 are assembled and secured to the free end of the pipe 13; then pipe 14 is extended through its respective portion of the lower casing and one end 60 secured to the T pipe 10; then parts 3, 7 and 11 are assembled and secured to the free end of the pipe 14; then pipe 15 is extended through its respective portion of the lower casing and one end thereof secured to the T pipe 11; then parts 4, 8 and 12 are assem-

bled and secured to the free end of pipe 15; then pipe 16 is extended through its respective portion of the lower casing and one end secured to the T pipe 12; then the nipple 18 is secured to the T pipe 9, and then 70 the nipple 18 and pipe 16 are joined by the pipe coupling 17. Then the upright or corner post pipes 19, 20, 21 and 22 are secured to their respective T pipes 9, 10, 11

and 12, and sleeves 23, 24, 25 and 26 placed 75 on their respective post. Then the upper portion of the frame canvas including parts 28 to 40 inclusive with the cover connected thereto are assembled in a manner similar to that employed in assembling the lower frame. That is the upper corner elbow 27 and nipple 40 are secured together and the extension 51 of elbow 27 inserted into the

upper end of post 19; then the top pipe 28 is extended through its respective part of 80 the upper casing and secured to the elbow 27; then the corner elbow 29 is secured to the free end of pipe 28 and its extension 51 inserted into the upper end of post 20; then

pipes 30 and 32 are connected by the T pipe 31 and inserted through their respective portion of the upper casing and the free end of pipe 30 secured to the elbow 29; then corner elbow 33 is secured to the free end 85 of pipe 32 and its extension 51 inserted into the upper end of post 21; then pipe 34 is inserted through its respective portion of the upper casing and secured to the elbow 33; then elbow 35 is secured to the free end of pipe 34 and its extension 51 inserted into 90 the upper end of post 22; then pipes 36 and 38 are connected by the T pipe 37 and inserted through their respective portion of the upper casing and the free end of pipe 36 connected to the elbow 35; then the coupling 95 39 is utilized to connect the free end of pipe 38 to the nipple 40. It is understood that, as the upper portion of the frame is assembled the sleeves 23, 24, 25 and 26 are screwed down so that the projections 51 on the corner 100 elbow can be inserted into the upper ends of their respective corner posts 19, 20, 21 and 22 to give slack to the canvas. After the cabinet is assembled and the ends of the canvas are secured together by automobile curtain fasteners well understood in the art, the sleeves are screwed upwards to make the canvas taut as indicated can be done by the position of parts in Figs. 4 and 5.

The assembly of the ridge pole pipe 45 105 and associated parts is well understood in the art and is therefore not described in detail. Any kind of a cot may be used inside of the cabinet. The curtains shown in Fig. 1 110 hang from the center to within one foot of the ground.

The central division of the curtain permits either part to be moved back and forth on the curtain rod so that a person may expose any part or all of the body to the sun's 115 120 125 130

rays. This method does away with cumbersome and awkward methods of shading that portion of the body which is not to be exposed, and also protects and shades the eyes and head without use of covers, shades, or goggles.

Various changes may be made without departing from the spirit of the invention as claimed.

10 We claim:

1. The sun and air bath cabinet set forth comprising a demountable frame having base pipes; corner post pipes with threaded upper ends that are supported by said base pipes; sleeves adjustably mounted on the threaded upper ends of said corner pipes; top pipes connected together and arranged to be loosely engaged and supported by said sleeves; a canvas detachably secured to and enclosing said frame, said sleeves adapted to be manipulated to increase or decrease the distance between said base pipes and top pipes to apply tautness or slackness to said canvas.

2. The sun and air bath cabinet set forth comprising a demountable frame having base pipes; corner post pipes with threaded upper ends that are supported by and secured to said base pipes; sleeves adjustably mounted on the threaded upper ends of said corner pipes; top pipes; elbows securing said top pipes together; projections from said elbows that are adapted to loosely extend into the open ends of said sleeves and corner posts; a canvas detachably secured to and enclosing said frame; said sleeves adapted to be manipulated to increase or decrease the distance between said base pipes and top pipes to apply tautness to or slackness to said canvas.

3. The sun and air bath cabinet set forth comprising a demountable frame having legs; base pipes secured to and supported by said legs; corner posts with threaded upper ends supported by and secured to said base pipes; sleeves adjustably mounted on the threaded ends of said corner pipes; top

pipes; corner elbows securing said top pipes together; projections integral with said elbows that are adapted to loosely extend down into said sleeves and corner pipes and prevent displacement of said top pipes; a canvas detachably secured to and enclosing said frame, said sleeves adapted to be manipulated to increase or decrease the distance between said base pipes and top pipes to apply tautness or slackness to said canvas.

4. The sun and air bath cabinet set forth comprising a frame having pipe legs; corner T pipes supported by said legs; base pipes secured to said T pipes that are arranged to form a rectangular enclosure; corner post pipes that have threaded upper ends secured to said T pipes; sleeves adjustable on the upper threaded ends of said post pipes; upper corner elbow pipes; projections integral with said upper elbow pipes that are adapted to be extended loosely downward into the open ends of said sleeves and post pipes to hold said upper elbow pipes in a predetermined position; and top pipes secured to said upper elbow pipes and arranged to form a rectangle corresponding to the rectangle formed by said base pipes, said sleeves adapted to be manipulated to force said top pipes a greater distance away from said base pipes or to permit said top pipes to descend by gravity toward said base pipes for the purpose specified.

5. The sun and air bath cabinet set forth comprising a frame having upper and lower detached portions; adjustable sleeves interposed between the upper and lower portions of said frame; corner elbows in the upper frame portion of said frame; and projections integral with said elbows and arranged to extend downward into said adjustable sleeves.

All of which claims are as substantially set forth and described in the foregoing specifications.

ANNA COLEMAN.
JOHN A. COLEMAN.
